HEATING INSTALLATION

Carl P. Benson, Bremerton, Wash.

Application May 29, 1939, Serial No. 276,381

5 Claims. (Cl. 237—51)

My invention relates to the heating of structures, residences in particular, and has for its object the conservation of heat and fuel, and the better application and control of the hot gases, smoke, etc. to the heating of the house.

In one specific aspect the invention has for its object the provision of means whereby more of the heat developed in a heater which is heated by an oil burner, for example, may be conserved or stored and applied to the heating of an upper floor of the building.

My invention will be best understood from a study of the accompanying drawings, wherein it is shown in a typical installation, and of the present specification and the claims which terminate the same.

Figure 1 is in part an elevation of the chimney, and in part a section through the same and through certain floors of a house, illustrating an installation made in accordance with my invention, the view being substantially along the line 1—1 of Figure 4.

Figure 2 is a section through the same at right angles to Figure 1, as indicated approximately by the lines 2—2 of Figures 1 and 4.

Figure 3 is a cross section at the upper level of the by-pass flue, and Figure 4 is a section adjacent the lower level of the by-pass flue, as indicated by the respective lines 3—3 and 4—4 of Figure 2.

Briefly stated, the invention proposes the construction of a chimney of material such as brick, masonry or the like, adapted to absorb and retain heat, having not only the normal vertical flue, but an alternative by-pass flue, the latter of which provides an elongated and circuitous path for the hot gases, mainly disposed at the level of the main floor, or that floor which is to be principally heated, although it may likewise extend upward to a floor above. Damper means are provided to control and direct the hot gases, so that they may, at the commencement of firing, when the chimney flue is cold, pass directly up the chimney with the least obstruction, but by means of which the hot gases, once circulation has been established, may be directed through the by-pass flue, thereby to heat up the brickwork at the main floor level, the brickwork absorbing the heat from the hot gases and giving it off slowly to the main floor level, and thus abstracting and putting to a useful purpose what would otherwise be waste heat. Provision is also made whereby the initial combustion may be either in a burner such as would be connected with a normal furnace in the basement, or a

fireplace or other burner at the main floor level. Provision is also made in appropriate cases, particularly where a fireplace is employed, and where the furnace heater is heated by a burner such as an oil burner that is in turn ignited and then totally extinguished, to discharge the air heated by the residual heat of the furnace into the fireplace and thence directly into the room itself.

The chimney is indicated generally by the numeral 1, and defines the usual or normal vertical flue 10, into which is connected at 12 the smoke pipe 21 of a furnace 2, and into the same vertical flue also connects a smoke outlet 11 from a fireplace 3. The furnace would customarily be located at the level of the basement, the floor of which is indicated at 20, and the fireplace is at the level of the main floor, indicated at 30. There may be also an upper floor, indicated at 40, and the masonry or brickwork 20 of the furnace may, if desired, be extended entirely through the main floor level to project into or through the upper floor level, as indicated at 14. The extension past the main floor level is, however, optional.

25 In the vertical flue 10, above the point of connection of the fireplace outlet 11 to the vertical flue 10, I provide a damper 5; suitable means, such as the handle 50, accessible from the main floor level or extended to any convenient point, 30 are provided for turning the damper, so that it may either close off this vertical flue or permit the same to be substantially freely open. In the drawings it is shown as closed. It would normally be opened when the chimney is cold and 35 it is desired to start a fire, in order to obtain the most direct upward draft and to heat the upper part of the chimney, and thus to start movement of the gases upwardly through the flue.

40 Below the level of the damper 5, but above the smoke connection at 12, and preferably not lower than the smoke connection at 11, is the entrance 60 from the flue 10 of a by-pass flue, the exit of which, back into the vertical flue 10, is at 61, 45 above the damper 5. Between the entrance 60 and the exit 61 the by-pass flue constitutes a path of appreciable length through the brickwork, so that when the damper 5 is closed and the hot gases are directed through the by-pass 50 flue the brickwork will be heated by heat abstracted from the hot gases, and will slowly give up this heat to maintain the temperature of the room. This result will occur, with the arrangement shown, whether the source of the heat is the burner 22 that heats the furnace 2 or a fire

in the fireplace 3. The particular nature and shape of the path afforded by the by-pass flue, and the points to which it extends, are largely immaterial. Since it would normally be intended only for heating the main floor level it would normally lie principally at the level of the main floor 30, that is, between the floor 30 and the floor 40, but it may extend, and in the present instance is shown as extending, in part above the level of the upper floor 40.

In the specific form shown, then, the by-pass flue extends from its inlet 60 downwardly, as indicated at 62, thence is offset to one side of the vertical flue 10, in this instance forwardly, as indicated at 63, near the level of the floor 30 itself. Thence it extends upwardly, as indicated at 64, and may extend as far upwardly as is convenient, at least to the extent that will not unduly diminish the draft and cause smoking, this extent depending upon the conditions obtaining in any given installation. As shown herein, the upward run 64 extends into the extension 14, and above the level of the floor 40, and at its upper end it then extends, transversely, to the opposite side of the vertical flue 10, as indicated at 65. Thence it extends downwardly, as indicated at 66, and at a low point, normally adjacent the level of the floor 30, it is offset again, this time oppositely to its offset 63, as indicated at 67, and then upwardly as indicated at 68 to its outlet 61 above the damper 5. It will readily be appreciated that the heat taken up from the hot gases by the brick-work in such a circuitous path is appreciable in amount, and when given off slowly from the bricks will materially assist in maintaining the temperature of the room.

The burner 22 which is shown is an oil burner, although a gas burner, for instance, will serve equally well. Preferably, though not essentially as to all phases of the invention, the burner is one which is ignited when needed and when the temperature of the house has risen to a sufficient degree the burner is completely extinguished. The interior of the furnace is usually lined with refractory brick and the like, and therefore absorbs and retains a considerable amount of heat from the flame of the burner 22. After the burner has been extinguished there is no longer any smoke nor odor from the burner, and air, which enters the furnace, plays upon the hot lining of the furnace, and tends to rise. Normally it passes out through the flue and is lost.

In the present installation I propose to make effective use of such hot air, and to that end I employ a damper 7, the position of which is controlled by the operating handle 10, this damper being located in the by-pass flue and movable to completely close off the latter or to leave the latter substantially freely open. When the damper 7 is open the operation is as described above. When the damper 7 is closed the hot air can no longer pass through the by-pass flue, and if the damper 5 is likewise closed, hot air arising from the furnace, and originating, for instance, from the air heated by the heated refractory brick lining of the furnace, cannot escape up the chimney flue, but instead is caused to pass out through the smoke outlet 11 into the fireplace 3 and thence out into the room, wherein is located the fireplace.

It has been found in practice that within a short time, three to five minutes, after the burner 22 has closed down, and while there is still a large amount of residual heat in the furnace, both dampers 5 and 7 can be closed, and a very

appreciable amount of warm air is thereby directed into the room, originating within the furnace, and the room is materially heated without any damage or discomfort from smoke, and without any odor. The damper 7 could not be thus employed if the source of heat were a coal stoker, for instance, since it could not be permitted to discharge carbon dioxide and in all probability carbon monoxide as well into the room, but where the burner is of a type which is intermittently ignitable and extinguishable the damper 7 is a valuable adjunct to the conservation of heat and fuel.

The fireplace 3 is in the present instance shown as equipped with a normal fireplace damper 31, controlled in its position by a chain 32 or other suitable means, but such a damper is largely superfluous in such an installation. It may be provided, however, to prevent escape of warm air from the room up the flue whenever conditions are such that heat might be lost in this manner. This, however, is the normal function of such fireplace dampers, and such loss of hot air from the room through the fireplace throat may be prevented by closure of the dampers 5 and 7, without the necessity of employing the damper 31.

It will be obvious that many changes may be made in the form and arrangement of the elements of my invention, and I have described only a typical form. Such changes, however, that incorporate the principles of my invention are still within the intended scope of the appended claims.

35. What I claim as my invention is:

1. Means for heating a house having a main floor and a lower floor, including, in combination, a chimney having a vertical flue extending through the floors, a fireplace at the main floor level having a smoke outlet connecting to the vertical flue, a heater at the lower floor level having a burner intermittently ignitable and extinguishable, and having a smoke outlet connected to the vertical flue, the chimney also having a by-pass flue leading from the vertical flue, and back into the same at a higher point, and affording an alternative path for the hot gases which is disposed principally at the main floor level, a damper in the vertical flue, above the fireplace smoke connection and between the inlet to and the outlet from the by-pass flue, movable to close off the vertical flue, to direct hot gases from either the heater or the fireplace through the by-pass flue, and a second damper in the by-pass flue, whereby if both said dampers are closed, to direct hot gases from the heater through the fireplace smoke outlet and into the room.

2. Means for heating a house having a lower floor and an upper floor, comprising a chimney having a vertical flue extending from the lower floor through such upper floor, a heater on the lower floor having a fluid fuel burner in its combustion space, and having a smoke outlet communicating between the fluid fuel combustion space and said flue, means operable to cut off supply of fuel to said burner for extinguishing its fire, a duct extending from said flue to the living space of said upper floor, and damper means in the vertical flue above the duct connection with the vertical flue, movable to close such flue after complete extinguishment of said burner fire by operation of said first means, for forcing air, supplied to said heater's combustion space after the fire therein is thus extinguished and heated

by the residual heat of such space, from said flue through said duct to the upper floor.

3. Means for heating a house having a lower floor and an upper floor, comprising a chimney having a vertical flue extending from the lower floor through the upper floor, a fireplace on the upper floor having a smoke outlet extending upward into the vertical flue, a heater on the lower floor having a fluid fuel burner therein, and having a smoke outlet communicating between the fluid fuel combustion space and said flue, means operable to cut off supply of fuel to said burner for extinguishing its fire, and a damper in the vertical flue above the fireplace outlet connection with the vertical flue, movable to close such flue after complete extinguishment of said burner fire by operation of said means, for forcing air, heated within said heater's combustion space by the residual heat of such space, from said flue downward through the fireplace smoke outlet to the upper floor.

4. Means for heating a house, comprising a heater having a fluid fuel burner therein, and having a smoke outlet from its combustion space to the atmosphere outside the house, means operable to cut off supply of fuel to said burner for extinguishing its fire, a duct extending down-

wardly and opening from its lower end into the living space of the house and affording communication with the heater's combustion space, and damper means in said smoke outlet movable toward closed position after complete extinguishment of said burner fire by operation of said first means, for forcing air, heated within said heater's combustion space by the residual heat of such space, downward through said duct to the living space of the house.

5. The method of heating a building, which comprises burning fluid fuel in a closed combustion space while discharging the noxious combustion gases only to the exterior atmosphere, and thereby heating the walls of the combustion space, shutting off supply of fluid fuel to the combustion space and thereby promptly discontinuing the production of combustion gases in the combustion space, thereafter interrupting direct communication between the combustion space and the exterior atmosphere, admitting relatively cool air to the combustion space to be heated by the residual heat stored in the walls thereof, and conveying such heated air from the combustion space into the living space of the building.

CARL P. BENSON.
